UNITED STATES PATENT OFFICE.

CARLYLE S. FLIEDNER, OF NEWARK, NEW JERSEY, ASSIGNOR, BY MÉSNE ASSIGNMENTS, TO THE PREST-O-LITE COMPANY, INC., OF INDIANAPOLIS, INDIANA, A CORPORATION OF NEW YORK.

INTERNAL-COMBUSTION ENGINE.

Application filed June 6, 1921. Serial No. 475,412.

This invention relates to internal combustion engines generally, and more particularly to an improved supercharger for air-cooled stationary internal combustion engines arranged to utilize air derived from the engine cooling system.

The fuel mixture drawn into an internal combustion engine cylinder by the piston on its suction stroke is somewhat rarefied, requiring a relatively large size cylinder for a given power output, and the present-day hydrocarbon fuels of high flash points are incompletely volatilized by the air component of the mixture which is drawn from the atmosphere past the vaporizer or carburetting device. The cooling air circulated about an air-cooled engine is usually discharged into the surrounding atmosphere.

The present invention contemplates utilizing a portion of the cooling air as a component of the combustible mixture and introducing it into the engine cylinder at a positive pressure, thereby introducing a full charge of hydrocarbon explosive vapor of a higher density and pressure than atmospheric; providing a higher volumetric efficiency, and obviating wire-drawing at the inlet valve. Inasmuch as the air derived is usually warm, the efficiency of the engine is increased because the hydrocarbon fuel employed is more completely volatilized.

The above and other objects and the novel features of this invention will be apparent from the following description taken with the accompanying drawings, in which

Fig. 1 is a side view of an internal combustion engine set embodying this invention, the casing and other parts thereof being shown in section,

Fig. 2 is an end view of the same, showing parts in section, and

Fig. 3 is an end view, on an enlarged scale, showing the casing and other parts in section and parts broken away.

According to the present invention, the fan that causes the flow of cooling air about the engine cylinder and associated parts, delivers a part of such warmed air under pressure to a conduit that communicates with the intake passage into which the fuel is discharged. The said conduit may also be connected to the crank case vent so as to draw the foul, oily vapors therefrom and discharge them with the combustible mixture

into the cylinder when the inlet valve opens. 55

For purposes of illustration, the engine E herein shown as embodying the present invention is of the vertical stationary air-cooled type, comprising a cylinder C having exterior radial fins C', as usual to promote the cooling thereof. The cylinder may be provided with suitable inlet and exhaust pipes I and X, controlled by suitable valves V and operating mechanism V'. A piston P in the cylinder C is connected to rotate a crank shaft K mounted in the crank case K'. A suitable fuel or gasoline supply valve G may discharge into a mixing pipe H leading to the inlet pipe I, and the crank case K' may be connected to the pipe H by a breather pipe B. The engine may be enclosed by a casing or hood A, that fits closely to the fins C' to provide a cooling air passage or jacket along the cylinder. 70

Suitable means may be provided to effect the circulation of air about the cylinder and to deliver the required warmed air to form the combustible mixture for the engine. For example, an exhaust fan may be employed and, in the particular arrangement illustrated, a flywheel F mounted on the crank shaft K has fan blades F' cast in the periphery thereof, forming a combined flywheel and fan. A portion of the casing projects outwardly and forms a cylindrical guard A' for the flywheel, a grating or perforated part N on the periphery thereof permitting the flywheel-fan to discharge the air into the atmosphere. The cooling air from the surrounding atmosphere may enter the casing A through another grating M at the upper end of the casing A, the air being drawn down over the cylinder and associated parts and discharged through the grating N. 90

According to the present invention, suitable means may be provided to collect a portion of the warm air discharged by the flywheel-fan and lead it to the inlet manifold I. As illustrated, a sheet metal duct or air scoop S may be arranged with its entrance opposite the exhaust side or periphery of the fan blades F', the size of the entrance of the scoop S depending upon the amount of air desired to be introduced into the cylinder with the fuel. A portion of the grating N may be cut out and the entrance of the scoop secured by flanges S' to the flywheel. 100

hood A'. From the flywheel hood the conduit in the scoop S may extend substantially tangentially in the direction that the air is thrown outwardly by the flywheel-fan. The 5 other end of the scoop S has an elbow that is connected at S'' to the breather pipe B so as to discharge into the latter. Furthermore, the scoop S may be tapered from its entrance toward its outlet, so as to increase 10 the pressure of the air therein. Accordingly, the fan acts as a compressor, as well as an exhauster, and forces a portion of the warm air therefrom through the scoop S into the breather pipe B near the upper end 15 of the latter, the air flowing from there through the mixing conduit H past the fuel valve G into the intake manifold I of the engine. The warm air more readily volatilizes the fuel admitted by the valve G and 20 is especially advantageous when hydrocarbon fuels of high flash points are used. By the arrangement described an explosive mixture under pressure will be built up in the conduit leading to the engine cylinder which 25 will be available for admission into the cylinder, as soon as the inlet valve opens or is uncovered. This insures a full charge of explosive vapor entering the cylinder at the same or higher density and pressure than atmospheric, and it is, therefore, unnecessary 30 for the engine to depend for its explosive charge on the suction produced by the movement of the piston downwardly. This makes for a higher volumetric efficiency and 35 also obviates wire-drawing at the valves. As heated air is necessary for more completely carbureting present-day hydrocarbon fuels, supercharging in this manner is particularly advantageous because the effect 40 of the loss of weight of the charge by heating is counteracted. Inasmuch as the power of the engine is dependent on the number of pounds of hydrocarbon vapor or explosive mixture that may be taken in, exploded and 45 exhausted per minute, higher power will be obtainable from the engine due to the increased density of the gas introduced by a positive pressure. Due to the higher volumetric efficiency and resulting higher power 50 output, a smaller sized engine may be used for the same power previously obtained with a larger sized engine running at the same speed, with the same valves, timing and proportioned parts. 55 The pressure that is built up may be varied by constricting or expanding the outlet of the scoop S in any desired manner as by means of a throttle valve, a butterfly valve, or a slide valve T. A valve H' may also 60 be provided in the pipe H and a control valve G' may be provided to regulate the fuel entering from the valve or carbureting device G.

Certain portions of the explosive mixture 65 escape from the cylinder past the piston

into the crank case, diluting the lubricating oil. By means of this improved supercharger, the air in the crank case may be kept under suction pressure, or lower than atmospheric pressure, since the heated air 70 from the scoop S acts as an ejector jet, as it enters the breather pipe behind the outlet of a tube B' connected to the vent in the crank case and, due to its velocity, draws the foul gas and oil vapor from the crank case through the tube B' and carries it along with the supercharged air into the intake pipe I. This prevents the accumulation of the residual ends of the hydrocarbons that leak past the piston rings and keeps them 75 from diluting the crank case oil, avoiding injury to the engine through the lowering of the viscosity of the lubricating oil. Furthermore, these high flash point ends of the fuel, under ordinary atmospheric pressure, will not evaporate, but will evaporate under the partial vacuum produced by the 80 ejector arrangement provided and will pass out of the crank case through the breather tube into the engine cylinder when the inlet 85 valve opens.

The improved engine may be employed for numerous purposes, as to drive a dynamo electric machine D that may be operable as a motor to start the engine and as a 90 generator to supply electric current for any purpose as for example, to charge storage batteries of houselighting outfits.

While the improvement is shown and described in detail, it will be understood that 95 various features thereof may be altered or omitted without departing from the spirit of the invention or sacrificing any of the advantages thereof.

I claim:

1. The combination with an internal combustion engine comprising a crank case and a cylinder having a mixture inlet, of a conduit establishing communication between said crank case and said mixture inlet, and means whereby air is discharged into said conduit at a point between said crank case and said mixture inlet and at a pressure above the normal intake suction pressure in said cylinder, so as to draw gas from said 110 crank case into said conduit and discharge such gas into said cylinder.

2. The combination with an internal combustion engine having a cylinder, an inlet passage therefor and a crank shaft, of an 120 air-cooling jacket about said cylinder, a device driven from said crank shaft for drawing air through said jacket to cool said cylinder and to warm such air, and a conduit leading from said device to said inlet passage whereby air so warmed is delivered to said cylinder as a component of the combustible mixture and at a pressure above the 125 normal intake suction pressure in said cylinder.

105

130

3. The combination with an internal combustion engine having a cylinder, an inlet passage therefor and a crank shaft, of a casing forming an air-cooling jacket about the cylinder, a fan on said crank shaft adapted to draw air through said cooling jacket, and means for utilizing a portion of such air as a component of the combustible mixture introduced into said cylinder, comprising a conduit having its entrance arranged opposite the discharge side of said fan to collect a portion of the warmed air discharged by the latter, said conduit having its outlet connected to said inlet passage whereby warmed air under positive pressure may be supplied through said passage to the cylinder.
4. The combination with an internal combustion engine having a cylinder and a mixture inlet, of a cooling jacket for said cylinder, a fan adapted to cause a flow of air through said cooling jacket, and a duct having its entrance arranged to receive warmed air discharged by said fan and having its outlet communicating with said mixture inlet, said duct having a portion tapering toward said outlet.
5. The combination with an internal combustion engine having a crank shaft, a cylinder, an inlet passage therefor, of an air-cooling jacket for said cylinder, a combined flywheel and fan on said crank shaft, said fan being adapted to cause a flow of air through said jacket to cool said engine, and a conduit having its entrance disposed opposite the discharge side of said flywheel-fan so as to collect a portion of the warm air discharged thereby, the outlet end of said conduit communicating with said inlet passage.
6. The combination with an internal combustion engine having a crank case, and a cylinder having a mixture inlet, of a casing providing a cooling-air jacket about said cylinder, a breather duct establishing communication between said crank case and said mixture inlet, a fan arranged to draw air through said cooling jacket, and a conduit having its entrance opposite the discharge side of said fan to collect warmed air therefrom and communicating with said breather duct and the inlet of said engine cylinder.
7. The combination with an internal combustion engine comprising a crank shaft, and a cylinder having an inlet, of a cooling jacket surrounding said cylinder, a combined flywheel and fan on said crank shaft arranged to draw air through said cooling jacket, and means for conducting part of the air discharging from said flywheel-fan to said inlet comprising a conduit having its entrance disposed opposite the periphery of said flywheel-fan and inclined in the general direction of rotation of the flywheel-fan and tapering toward the discharge end thereof, said duct communicating with said inlet.
8. The combination with an internal combustion engine having a crank case provided with a vent, a cylinder having a mixture inlet, a duct leading to said inlet, a duct leading from said vent and having an outlet opening into the first-mentioned duct, of a casing forming a cooling jacket for said cylinder, a fan producing a flow of air through said jacket, and a conduit having an inlet arranged to collect warm air exhausted by said fan, such conduit communicating with said inlet and discharging rearwardly of the outlet of said second duct, whereby gas from the crank case is drawn into the first-mentioned duct by the stream of warm air from said conduit.
9. The combination with a stationary air-cooled internal combustion engine comprising a crank case, a horizontal crank shaft, a vertical cylinder having a mixture inlet, and a breather duct between said crank case and said mixture inlet, of a hood or casing forming an air-cooling jacket for the cylinder, a fan mounted on the crank shaft and arranged to draw air through said cooling jacket and discharge the same peripherally, and an air collecting device or scoop having its entrance disposed opposite the periphery of said fan and arranged to collect air discharging under pressure therefrom, said scoop communicating with said mixture inlet through said breather duct.
10. In an internal combustion engine, the combination with a cylinder having a mixture passage, fuel supply means discharging into said passage, a crank shaft, a combined flywheel and fan mounted on said crank shaft and arranged to produce a flow of air over said cylinder, and a duct having its entrance arranged opposite the exhaust of the flywheel-fan to collect warm air discharging therefrom and having its outlet arranged to discharge said warm air across the inlet of said fuel supply means.
11. The combination with an internal combustion engine comprising a cylinder, a piston working therein, a mixture inlet for said cylinder, a crank case, an air cooling jacket for said cylinder and a conduit establishing communication between said crank case and said mixture inlet, of means for moving air through said jacket to cool said cylinder; and means whereby part at least of the air thus warmed is delivered to said conduit at a pressure at least equal to the normal suction of such engine, whereby gas and vapor are carried from said crank case to said cylinder.
12. The combination with an internal combustion engine comprising a cylinder, a mixture inlet therefor, a piston working in said cylinder, a crank shaft connected to said piston, a crank case, and a conduit connecting

said crank case and said mixture inlet; of a combined flywheel and fan mounted on said crank shaft; casing means forming a cooling jacket for said cylinder and partially enclosing said flywheel-fan, whereby the latter is adapted to produce a flow of air through said jacket; and a duct having an inlet communicating with said casing means at a point opposite the periphery of said flywheel-fan to receive warmed air discharged

from the latter, said duct discharging warmed air into said conduit at a pressure greater than the normal suction of said engine, whereby gas and vapor from said crank case as well as a greater weight of 15 warmed air are carried to said cylinder during the suction stroke of said piston.

In testimony whereof, I affix my signature.

CARLYLE S. FLIEDNER.
